UNITED STATES PATENT OFFICE.

EMIL ANDERSON, OF NEW YORK, N. Y., ASSIGNOR TO H. STANLEY TODD, OF NEW YORK, N. Y.

TURBINE.

1,072,295.

Specification of Letters Patent. Patented Sept. 2, 1913.

Application filed December 8, 1910. Serial No. 595,331.

To all whom it may concern:

Be it known that I, EMIL ANDERSON, a citizen of the United States of America, and a resident of New York, county of New York, and State of New York, have invented certain new and useful Improvements in Turbine-Engines, of which the following is a specification, reference being had to the accompanying drawings, forming a part thereof.

My invention relates to turbine engines, and particularly to reversible turbine engines, and my invention consists, first, in a novel form and construction of valve operating means for reversing the direction of running of the engine; second, in supplemental actuating elements and governing means therefor, automatically controlled in accordance with the speed of the engine; third, in means whereby the supplemental actuating means may be brought into play regardless of the speed of the engine at the time the reversing means is operated; fourth, in auxiliary actuating means arranged to be manually brought into play if desired at the time of first starting up the engine; fifth, in means for regulating the admission of motive fluid to the main actuating elements; and sixth, in automatic governing means for controlling the same in accordance with the speed of the engine.

The main objects of my invention are, first, to provide a simple and powerful reversing turbine engine which will operate efficiently and economically in either direction; second, to provide that the same may be reversed either from a condition of rest or when running at high speed; third, to employ the power of the engine itself to bring about the adjustment of parts necessary for a complete reversing operation, whereby in large plants the amount of work imposed upon the operator will be not excessive and the use of independent power means for the purpose will be obviated; fourth, to provide for an increase of power in the engine above the maximum obtainable under the ordinary operation thereof so that while the engine may be operated at the highest economy under normal conditions, a reserve may be called upon under abnormal conditions such as a sudden, heavy over-load, or when suddenly reversing the engine at a time it is running at considerable speed, such reserve being in itself

not necessarily economical in its operation, but designed to powerfully supplement the action of the main actuating elements; fifth, to automatically regulate the admission of motive fluid in an economical manner under 60 normal conditions of running whereby the engine may normally run in an economical manner under a varying load.

My invention also consists in many novel details of construction and combinations of 65 parts, such as will be fully pointed out hereinafter, and advantages other than those specifically pointed out above will be apparent to those skilled in this art; and in order that my invention may be fully understood I will now proceed to describe in detail a construction constituting an embodiment thereof, and will then point out the novel features in claims.

In the drawings: Figure 1 is a view in end elevation of an engine constructed in accordance with my invention. Fig. 2 is a view in part end elevation and part vertical transverse section of the engine looking toward the opposite end thereof. Fig. 3 is a 70 view in central longitudinal section therethrough, the rotary element and certain parts carried therewith being shown in side elevation. Fig. 4 is a detail view of parts of the engine upon a larger scale looking 75 in the direction of Fig. 1, certain of the parts being shown in end elevation and other parts in vertical transverse section. Fig. 5 is a detail view on a still larger scale 80 in central vertical section through certain parts of the engine showing particularly the governor mechanism. Fig. 6 is a top view of the engine upon a reduced scale with certain parts omitted, the said view showing 85 particularly certain features of the reversing mechanism. Fig. 7 is a detail vertical transverse sectional view through one of the stationary abutment elements or rings of the stationary casing, the section being taken upon three different planes to illustrate different groups of reaction recesses employed therein. Fig. 8 is a detail horizontal sectional view showing a means employed for adjusting the point of admission of high pressure motive fluid. Fig. 9 is a detail view 90 showing one of the supplementary reversing valves in transverse section, and a portion of the casing in which the same is mounted. Fig. 10 is a detail sectional view through a 95 part of the rotary element and a portion of 100 105 110

one of the supplementary reversing valves showing the relation of the supplementary buckets in the rotary element with certain co-acting recesses in the said valve. Figs. 5 11 and 12 are detail sectional views showing the co-action of a part of one of the supplementary valves with a stud or stem employed in connection with the reversing mechanism. Fig. 13 is a detail sectional view of a manual operating element for the high pressure admission adjusting means illustrated in Fig. 8. Fig. 14 is a detail fragmentary view in end elevation showing in part the connections employed for automatically adjusting such means. Fig. 15 is a detail view in longitudinal section of an auxiliary starting head and nozzle employed, together with certain correlated parts. Fig. 16 is a detail transverse sectional view showing one of the main inlet and reversing valves, and also showing in rear elevation one of the adjustable high pressure inlet elements. Fig. 17 is a detail top view of a part of the governor mechanism employed. Figs. 18 and 19 are views respectively in central longitudinal and transverse section of a coupling employed. Fig. 20 is a diagrammatic view in development looking down upon the rings 25 and upon the periphery of the rotary impelling element.

The general form of engine illustrated herein is that shown in a co-pending application Serial Number 590,175 filed November 1, 1910, and to which reference is hereby 35 made for a specific and detailed description thereof. In general the engine comprises a stationary casing 20 provided with end heads 21-21, and a rotary impelling element 22 mounted upon a central drive shaft 40 23 which is journaled in suitable bearings 24-24 carried by the end heads 21-21. The casing 20 has a substantially cylindrical bore therein concentrically arranged with respect to the axis of rotation, and secured fast there- 45 in within the said bore are two rings 25-25 constituting stationary abutment elements in which the reaction surfaces for the motive fluid are contained. The rotary impelling element 22 has a central flange 26 and two end 50 flanges 27, the former of which is arranged between the two rings 25-25 and the latter of which are arranged upon the outside of the said rings, the said flange portions being provided with buckets for receiving 55 the motive fluid and which are designed to act in conjunction with the reaction surfaces above referred to.

The rotary impelling element has two sets of high pressure buckets arranged one upon 60 either side of the central flange 26, and two sets of low pressure buckets arranged upon the inner faces of the flanges 27. These buckets are arranged in the form of concentric rings 28-29-30 and 31, as appears in 65 Figs. 4 and 15, there being four of such

rings of buckets in the present example of my invention, and three sets or rings of low pressure buckets 32-33 and 34 of larger size as appears in Fig. 15. The complementary reaction recesses in the stationary rings 70 25 are arranged in groups as appears in Fig. 7. There are three similar groups 35 of these high pressure reaction surfaces equidistantly disposed around the rings for each set of high pressure buckets, each group 75 comprising four sets concentrically disposed and constituting segments of rings. The length of the ring segments decreases from the outer set to the inner set as is clearly shown in Fig. 7, and the sets commence 80 progressively at a later period in the direction of the rotation of the engine, and which is indicated by the arrow in Fig. 7. The ring segments end at about the same radial line and in proximity to transfer valves 36, 85 as will presently be described. The ring segments communicate with one another through cross-over passages 37 at their front and rear ends, and at the forward end thereof they communicate with transfer passages 90 38 which connect with the said transfer valves.

Located intermediate the groups 35 upon the same side of the rings 25 are three other groups of reaction surfaces 39 (see Fig. 7). 95 These groups also constitute high pressure reaction surfaces for coaction with the high pressure rings or buckets, but are arranged to be used when the engine is running in a reverse direction to that shown by the arrow 100 in Fig. 7. For convenience of description herein I will refer to the direction of rotation of the engine indicated by the arrow in Fig. 7 as the "forward" direction of drive, and the opposite direction as the "reverse" 105 direction of drive. The ring segments of the group 39 decrease in length progressively in an outward direction because, as will presently be shown, the motive fluid under reverse direction of drive is admitted 110 to the innermost set first and passes thence outward through the outer sets or ring segments. Upon the opposite side of each of the rings 25 there are three groups of low pressure reaction surfaces 40 complementary 115 to the high pressure groups 35 and arranged for coaction with the low pressure rings of buckets in the flanges 27 of the rotary impelling element, and three other groups of low pressure reaction surfaces 41 intermediate 120 the groups 40, complementary to the high pressure groups 39 and arranged for coaction with the rings of low pressure buckets in the flanges 27 of the impelling element. The segmental sets of reaction surfaces of each group have cross-over passages 42 connecting them in a manner similar to the cross-over passages 37 of the high pressure sets, and also transfer passages 43 which connect with the said transfer valves 125 130

36. The transfer valves 36 are of cylindrical plug-like form and have outer and inner transfer ports or passages 44 and 45, the inner passages serving to connect the high pressure groups 35 with the low pressure groups 40 in advance thereof (in the direction of the arrow in Fig. 7) when the valves are set in one position, and the transfer passages 44 serving to connect the high pressure groups 39 with the low pressure groups 41 in advance thereof, in a direction opposite to that of the arrow in Fig. 7 when the valves are set in their opposite position.

Motive fluid, hereinafter referred to as "steam," though other motive fluids may of course be employed, is admitted at three points around the casing through main valves 46. Each of these main valves includes a disk or flange having two openings 47 therein (Fig. 20) a line drawn through the said openings being upon one side of the axis of rotation of the said valve. The valves are adapted to be rotated, as will presently be explained, so that they may be adjusted to either of two positions. When the valves are adjusted to the position shown in the diagrammatic view Fig. 20, the openings 47 therethrough will register with openings or passages 48 in the casing, such as lead to the outermost rings of the high pressure buckets 28 in the impelling wheel and to the outermost sets of reaction surfaces of the groups 35 in the stationary abutment rings 25. In the operation of the engine in the forward direction the steam will pass backward and forward between the reaction surfaces in the said first set of the groups 35 and the high pressure buckets in the rings 28 until the second set of high pressure reaction surfaces of the sets 35 are reached, when the area of the second said sets of reaction surfaces and the area of the corresponding buckets will be added to the area of the first set, and the steam thereby expanded to a greater volume. The same action will continue when the third set of reaction surfaces are reached, at which time the steam will be again expanded, and the steam will be still further expanded when in like manner the fourth set of reaction surfaces are reached. From this point the steam will pass through the transfer passages 38 to the transfer valves 36, and thence through the inner passages 45 therein to the low pressure set of buckets and reaction surfaces upon the opposite side of the said stationary abutment rings 25, passing first to the innermost sets of the low pressure reaction surfaces of the groups 40 and the innermost low pressure rings of buckets 32, and thence outward successively through the intermediate and outer sets of the low pressure reaction surfaces of the groups 40 and the intermediate and outer sets of the low pressure buckets 33-34 until the steam

is finally exhausted into an annular exhaust chamber 49 in the casing. The course of the steam may be readily traced in the diagrammatic view Fig. 20, the direction thereof and the direction of the rotating member being in the direction of the arrow shown in connection with that figure.

When it is desired that the engine be run in a reverse direction, *i. e.*, in a direction opposite to that shown by the arrow in Figs. 7 and 20, the main valves 46, which it will be noted act as reversing valves, will be rotated through an arc of 180 degrees. At such time the openings or passages 47 therein will come into register with openings or passages 50, closing the aforesaid passages 47. When the valve is so adjusted the steam admitted through the openings 47 to the passages 50 will pass first to the innermost sets of reaction surfaces of the groups 39-39 in the stationary abutment rings 25-25 and the corresponding inner ring of high pressure buckets in the rotary impelling wheel, thence as the rotary impelling element revolves and the outer sets of stationary reaction surfaces are successively reached and their area, together with the area of the successive outer rings of buckets are added, the steam will be expanded through successive stages until the upper passages 44 of the transfer valves 36 are reached. These transfer valves must be given a movement of rotation to the required extent to bring the openings 44 in register with the transfer passages leading respectively to the discharge end of the high pressure groups of reaction surfaces 39 and the approach end of the complementary low pressure groups 41, and the manner in which this is preferably accomplished will be presently explained. Thence the steam will be again expanded through successive stages until, in like manner as described above, it reaches the annular exhaust chambers 49.

The general preferred form of the buckets may be seen by reference to Figs. 8 and 20, each bucket comprising an elongated recess 51 having a central bridge wall 52 at the mouth thereof, whereby a separate receiving and discharge orifice is provided. The reaction surfaces which are in the form of channels are adapted to successively connect the discharge end of each bucket with the receiving end of the next succeeding bucket, the said channels having a rearwardly turned portion 53 at the receiving end thereof, and a forwardly extending portion 54 at the forward end. By this means steam entering a bucket will be projected against the bridge wall thereof and against the forward end or wall of the bucket, being deflected and turned backward by the said forward end into the rearwardly extending portion 53 of the reaction surface or channel, to be turned by reason of the shape of the channel

and again forwardly projected into the next succeeding bucket. The buckets being symmetrically formed are adapted for engagement with reaction surfaces pointing in either direction and hence are equally adapted for co-operation with the aforesaid reaction surfaces for forward driving as well as for rearward driving.

As so far described the engine is substantially that set forth in the application for Letters Patent above referred to. In addition, however, to the buckets on the inner faces of the flange 27 and the outer faces of the flange 26, the impelling element is provided in the present instance with two sets of supplementary buckets 55, each set constituting an annular ring of such buckets, one of such rings being arranged upon either side of the said impelling wheel. Steam is admitted to the buckets 55 through supplementary reversing valves 56, there being three of such valves upon each side of the engine symmetrically disposed around the axis thereof, each valve being provided with relatively stationary reaction surfaces 57 for coaction with the said buckets 55, as clearly appears in Fig. 10. Actually each of the valves is provided with two inlet channels 58-59, and two sets of diametrically opposed reaction surfaces 57 near the outer edge thereof and in communication respectively with the said inlet channels 58-59. The said reaction surfaces of the two sets are disposed so as to face in opposite directions whereby the one in connection with the channel 58 will project the steam against the buckets in a direction for forward driving, and the set in connection with the inlet channels 59 will project the steam in the opposite direction, *i. e.*, in a direction to rotate the impelling wheel for reverse driving. Steam is admitted at certain times as will be presently explained, through a supply pipe 60 to an annular chamber 61 in the end heads 21 of the casing, whence it passes through the inlet channels 58 in the valves 56 when the valves are adjusted in the position in which they are shown in the drawings, and so to the supplemental buckets 55 in the impelling wheel. When the valves are in the position shown, the channels 59 are out of register with the chamber 61 so that no steam will be admitted thereto, but if the valves are rotated through an arc of 180 degrees then the admission of steam to the channels 58 will be cut off and steam will be admitted in lieu thereof to the channels 59. Each of the valves 56 is provided with a peripheral set of gear teeth 62, the teeth of the three valves upon each side of the rotary impelling element being disposed in mesh with the teeth of central pinions 63 disposed upon the shaft 23, one upon each side of the said rotating impelling wheel. Each of the pinions 63 is provided with an elongated

hub 64 to which it is secured by a splined connection, that is to say, the hub may be moved longitudinally with respect thereto, but the said hub and wheel are secured together against relative rotative movement. The forward and rear ends of these sleeves or hubs 64 are provided with clutch teeth 65 and 66 respectively, the former arranged for co-engagement with clutch teeth 67 upon the rotating impelling element, and the latter for co-engagement with clutch teeth 68 carried by the stationary end head of the casing. The normal running condition of the parts is with the clutch teeth 66 of the sleeves or hubs 64 in engagement with the stationary clutch teeth 68 so that the pinion 63 and the valves 56 are held stationary. Under certain conditions, however, the hubs or sleeves 64 may be moved longitudinally inward to relieve the clutch teeth 66 from engagement with the teeth 68 and to cause the engagement of the clutch teeth 65 thereof with the clutch teeth 67 of the rotary impelling element. Under such conditions the valves 56 will be rotated by and in accordance with the rotary movement of the rotary impelling wheel. This is effected when it is desired to reverse the position of the valves 56 as aforesaid, and with the particular construction shown in which the pinions 63 are one-half the diameter of the gear teeth 62 of the valves 56, one complete revolution of the rotary impelling wheel will move the said valves 56 through the 180 degrees necessary to reverse the position of the reaction surfaces thereof with respect to the supplemental impelling wheel buckets. The sleeves or hubs 64 are normally held in their outward position with the clutch teeth 66 thereof in engagement with the stationary clutch teeth 68 by means of shipper levers 69. These shipper levers have a rocking movement in the direction of the axis of the shaft 23 upon a stationary pivot 70 (see particularly Figs. 2 and 4), and in addition to this movement they also have a limited angular movement about the said axis to the extent permitted by the clearance between blocks 71 to which the levers 69 are pivoted and abutments 72 to which the pivot pins 70 are secured.

A spring 73 tends to normally force the levers in one direction while an operating handle 74 connected with the said levers by connecting elements 138, is provided for moving the said levers in the other direction. In the drawings they are shown in their positions as when moved by the contraction of the spring 73, such being their normal rest positions and in such position they are pressed outward longitudinally of the axis of the shaft 23 by means of studs 75, the studs being in turn forced outward by cams 76 carried by the uppermost supplemental reversing valves 56. The man-

ner in which this mechanism is operated is as follows: Assuming the engine to be running in the direction of the arrow in Fig. 4 and it is desired to reverse it, the position 3 of the hand lever 74 is reversed, that is to say, it is thrown down from the position in which it is shown in the drawings. The result of this is three-fold,—first, it brings about the reversal of the supplemental reversing valves 56; second, it reverses the position of the main valves 46; third, it reverses the position of the transfer valves 36. One of the first effects of its movement is to slightly rotate the shipper levers 69 about the axis of the shaft 23 against the resistance of the spring 73. As soon as the front ends of these levers 69 move clear of the pins 75, helical springs 77 which surround the shaft 23 and bear against the sleeves 64 and hence against the lever 69, will force the said levers and sleeves inward with the result that the clutch teeth 68 of the said sleeves will be released from their engagement with the stationary clutch teeth 68 and the clutch teeth 68 caused to engage the teeth 67 upon the rotating element. In the further forward movement of the rotating element the valves 56 will be rotated through the required distance (in the present instance one-half of a revolution) as has been above described. Directly the valves 56 begin to rotate, the lower cam elements 76 thereof will release the studs 75 and the said studs will be withdrawn under the influence of small coil springs 78 with which they are provided. This will release the shipper levers 69 and permit them to return to their normal angular positions under the influence of the springs 73, but so far 40 they will remain forced inward under the influence of the springs 77 and will so remain until they are again forced outward by the action of the studs 75. They will be so forced outward as the valves complete their half revolution by reason of the fact that the opposite cams 76 thereof will reach the said studs and will force them outward. In so forcing the studs outward the movement thereof will be imparted to the shipper levers and the shipper levers will be forced outward longitudinally of the axis of the shaft 23 against the resistance of their springs 77 back to their original position, wherein the sleeves 64 are released from engagement with the rotating element and are caused to engage the clutch teeth 68 upon the stationary casing.

The movement of the supplemental reversing valves will be imparted to the main reversing valves 46 through gear trains (see Figs. 2 and 3) including pinions 79 upon the supplemental valves 56 upon one side of the engine, idler gears 80 in mesh therewith, pinions 81 in mesh with the idler gears 80, and bevel gears 82 which connect the

pinions 81 in driving relation with the main valves 46. The one-half of a revolution imparted to the supplemental valves will thus in like manner be transmitted to the main valves.

The transfer valves 36 are moved by a direct connection with the operating lever 74 as follows: The stems of the valves 36 are provided with bevel gears 83 which are arranged in mesh with complementary bevel gears 84 secured fast upon rock shafts 85—86 disposed around the engine in proximity to each pair of the said valves 36, the said rock shaft 86 serving also as a support for the operating handle 74. Each of the rock shafts 85 is provided with an operating arm 87 while the rock shaft 86 is provided with two such operating arms 88—88 (see Fig. 2), and links 89 connect the operating arms 88 of the rock shaft 86 with the operating arms 87 of the rock shaft 85. When the operating handle 74 is manipulated as aforesaid to reverse the engine, such movement results in rotating the transfer valves to the required degree to reverse their positions. To again reverse the engine, the operating handle must be moved up to its original position as shown in the drawings, and the foregoing operations will then be repeated, the transfer valves being moved back to their original positions the revolution of the main and supplemental reversing valves completed.

The foregoing operation of reversing the engine presupposes that the engine shall be revolving at the time, because while the manipulation of the operating handle 74 actually reverses the transfer valves, it merely operates the clutch mechanism by which the rotating element in its movement is caused to reverse the position of the supplemental reversing valves 56 and the main valves 46. To provide therefore for starting the engine in a reverse direction from a condition of rest, I have provided the rotating element upon either side thereof with a set of auxiliary bucket recesses 90 (see Figs. 2 and 15) and the casing with a stationary head 91 containing two nozzles 92—93, and a valve 94 by which either of the said nozzles may be supplied with motive fluid from a branch connection 95. When it is desired to start the engine in a reverse direction from that in which it was rotating when it last came to rest, the valve 94 may be adjusted so as to connect the steam supply with the proper nozzle 92—93, wherein an initial impulse may be given to turn the rotating element. At such time the position of the operating handle 74 should also be reversed so that the rotating element in its first movement will reverse the position of the main and supplemental valves whereupon the main supply valve (not shown) may be opened to admit steam and the engine thereupon operated in

the normal manner as was described hereinabove.

I preferably provide a coupling for the engine shaft such as will relieve the engine 5 from load at the time it is being reversed or started up in a reverse direction, and in Figs. 18 and 19 I have shown a convenient form of such coupling. In this construction the engine shaft 23 is provided with a sliding 10 nut 96 having a splined connection with the said shaft, whereby it may slide freely thereon, but is secured to rotate therewith, the said nut having a screw-threaded engagement with a casing 97 in which the 15 shaft 23 rotates freely. The casing 97 is, however, secured fast to the driven shaft 98, being provided with a flanged hub 99 for this purpose. The casing 97 carries rocker arms 100 which are pivoted thereto, the said 20 operating arms having portions 101 for engaging a cam surface 102 upon the nut, and with fingers 103 for engaging a collar 104 which is secured fast to the shaft 23. When the nut is in either of its extreme positions 25 longitudinally upon the shaft 23, the cam surface either at one end or the other will so bear against the portions 101 of the arms 100 as to force the fingers 103 into such engagement with the collar 104 as to lock the 30 casing 97 to the collar 104 and hence lock the shafts 23 and 98 together. When, however, the shaft 23 is reversed the effect will be to cause the nut 96 to travel to a position opposite to that formerly occupied thereby, 35 and while in its intermediate position the cam surface 102 is so formed as to release the arms 101 whereby the fingers 103 will be disengaged from the collar 104 and hence during the greater part of such movement 40 the two shafts will be disconnected. Thus it will be seen that each time the shaft 23 is reversed it will be permitted to rotate during substantially the entire time it takes the nut to travel from one extreme position 45 thereof to the other, free of connection with the driven shaft 98 and hence relieved of load.

I have provided automatic governing means for the engine, the same comprising 50 two sets of governor elements 105—106, (Figs. 3 and 5) the former to control the admission of steam to the main high pressure rotating element buckets, and the latter to control admission of motive fluid to the 55 supplemental reversing valves. The governor mechanism includes a vertically mounted rotatable spindle 107 actuated by means of a worm and gear connection 108 from the main shaft, a collar 109 carried 60 thereby, centrifugal weights 110 for the said lower governor element 105, and centrifugal weights 111 for the said upper governor element. The centrifugal balls 110 of the lower governor element 105 are connected 65 with bell cranks whose shorter arms en-

gage a collar 112 upon a sleeve 113 mounted to slide upon the vertical spindle 107. This sleeve 113 has another collar 114 which is engaged by a rocking arm 115, the latter being connected by means of a link 116 with an operating arm 117 upon a rocker spindle 118. The said rocker spindle extends into the casing and is provided with pins 119 for engagement with studs 120 upon adjustable blocks 121 mounted in proximity to the outermost rings 28 of high pressure buckets of the main rotating element (see particularly Figs. 5, 8, and 16), each block being provided with an admission nozzle 122 for steam at a point therein wherein a portion thereof will come more or less into register with the high pressure inlet channels 48 leading to the passages 47 in the uppermost main reversing valve, and as the block is adjusted forward or backward the registry 80 between the nozzle openings 122 and the inlet channels 48 will be more or less perfect whereby the amount of steam admitted therethrough may be proportionately regulated. In addition to the actual variation 85 of the amount of steam admitted, the adjustment of this block, which itself contains certain of the reaction surfaces for co-engagement with the high pressure ring of buckets 28, with respect to others of the said 90 reaction surfaces, will cause a more or less perfect and correct registration of the buckets and reaction surfaces in their entirety, whereby the efficiency of the steam action thereon will be increased or decreased 95 in accordance therewith.

By reason of the connection of the governor element 105 with the adjustable blocks 121, it will follow that their position will depend upon the action of the governor, and the connections are so arranged that steam will be gradually cut off and its efficient action upon the rotating element reduced in proportion as the speed of the governor increases above a predetermined rate while 100 on the other hand the amount of steam admitted will be increased and the efficient action thereon upon the rotating element will also be increased in proportion as the speed of the governor decreases.

Each of the high pressure inlets may be provided with similar automatically controlled mechanism if desired, but in the present instance I have shown the other two high pressure inlets as merely provided with a manually operated means for adjusting the position of the blocks 121, such means comprising a handle 123 mounted directly upon the spindle 118 and a spring-pressed locking arm 136 arranged 115 for engagement with studs 137 for the purpose of locking the blocks in their finally adjusted position.

The upper governor element 106 is arranged to control the position of a throttle 130

valve 124 by which steam is admitted to the branch pipes 60 leading to the supplemental reversing valves 56. The stem of this valve 124 is provided near the outer end thereof 5 with a collar 125, and a spring 126 bears against the collar and normally tends to force the valve 124 open. The collar 125 normally rests at one side thereof upon the slotted end of a lever 127, the said lever in 10 turn resting upon the uppermost flange 128 of a sleeve 129 mounted to slide upon the governor spindle 107. The short arms of the bell crank levers which support the governor weights 111 engage a grooved collar 130 carried by the lower end of the said sleeve 129, whereby the sleeve will be caused to rise as the governor balls fly out and will be pulled down as the governor balls move inward. The parts are shown 15 in Fig. 5 of the drawings in the normal running condition of the engine, in which the engine is rotating at a speed to cause the governor balls to fly out sufficiently to lift the sleeve 129 to a point wherein the valve 20 124 is forced to its seat and steam is therefore cut off from the supplemental actuating means. This is because the supplemental actuating means is only intended to be used under abnormal conditions, the 25 steam used at such points being used substantially non-expansively and hence very much less economically than the steam which is used in the main actuating elements of the engine. Should the speed of 30 the engine fall below a predetermined point, however, the action of the governor balls in moving inward will open the throttle valve 124 and steam will be admitted to the auxiliary buckets and in this 35 manner the power of the engine will be augmented. After the speed of the engine has reached a point wherein the governor balls have flown out to a position wherein the valve 124 is closed, a further rise of 40 speed of the engine will begin to effect the cutting off of the admission of steam to the uppermost high pressure channels in the form of engine shown, and to any of the other channels as may be desired, and as the 45 speed of the engine continues to increase steam may be gradually cut off until finally it is cut off entirely in the extreme adjusted position of the blocks 121.

The governor element 105 is the element 50 which regulates the engine under ordinary conditions, the ordinary running speed of the engine being such as to require the blocks 121 to have been moved somewhat, after the governor element 106 has reached 55 the limit of its movement. Thus fluctuations of speed for a certain amount below such predetermined speed and to any extent above will be taken care of by the governor element 105, but on the other hand, 60 should the speed of the engine fall below a

predetermined point wherein the main actuating elements are receiving all the steam that can be supplied to them, then the supplemental governor element 106 will come into play and steam will be admitted to the 70 supplemental buckets to assist in the actuation of the engine as aforesaid.

When the engine is rotating in one direction at a high speed, *i.e.*, such a speed wherein the valve 124 is entirely closed, and it be 75 desired to reverse the engine quickly, it is highly desirable that after the reversing and main valves have been properly adjusted, steam be admitted through the supplementary reversing valves to the supplementary 80 buckets, but as so far explained the throttle valve 124 will be closed at such times because of the speed at which the engine is running. I have, therefore, provided means for opening the throttle valve 124, regardless of the position of the governor balls 111, whenever the position of the main valves is reversed for the purpose of reversing the direction of running of the engine. This means includes a disk 131 secured fast upon 85 the stem 132 of the uppermost main valve 46, such disk being provided with two uprising studs 133 (see Figs. 5 and 17) and two springs 134. The lever 127 is loosely mounted upon the upper extremity of the spindle 132 and is adapted to be engaged by the 90 said studs 133 and the springs 134. When the position of the main valve 46 is reversed the stud 133 farthest away from the lever 127 will move around to a position wherein 95 it will engage the said lever and in the further movement of the valve will carry the lever over with it to a point wherein the slotted extremity thereof will be relieved from engagement with the collar 125 upon 100 the stem of the valve 124, and the spring 126 will then act to open the valve, the collar 125 being received at such times within the said slotted portion of the lever. In the completion of the angular movement of the 105 valve 46 the lever will be moved over to a position wherein the opposite end of the slot reaches the collar 125, at which point the collar will act as a stop for the lever, and in a slight further movement of the valve 110 46 the spring 134 which by this time will have engaged the lever 127 will be compressed. Thereafter as the speed of the engine reduces to zero, as it will in the reversing movement before starting in the opposite direction, the governor balls 111 will move in to a point wherein the sleeve will be so lowered as to carry the end of the lever 127 down beneath the collar 125, at 115 which time the spring 134 will complete the movement of the lever, the said lever 127 reaching a point wherein the slotted extremity thereof will again rest beneath the collar 125 as shown in Fig. 7, except that the 120 angular position of the disk 131 and the le- 130

ver 127 will be reversed. Thereafter as the speed of the engine increases in a reverse direction the lifting of the sleeve 129, due to the flying out of the governor balls 111, 5 will lift the end of the lever 127 and the collar 125 until the valve 124 is again closed and the engine will then operate normally as before. It is understood that the lever 127 is so loosely mounted, or is so otherwise constructed that it may have a free vertical movement to the required extent as well as an angular movement about the axis of the valve 47. A spring 135 tends to draw the lever downward so that its slotted extremity 10 will be brought into constant engagement with the upper face of the flange 128 of the slot 129, whereby it will follow the movements thereof.

While a large part of the invention herein is directed specifically to the reversing feature of the engine, it will of course be obvious that certain novel features contained in the governing means and the introduction of supplemental actuating means there- 25 by at a time of over-load, may be advantageously employed independently of the reversing engines.

What I claim is:

1. In a turbine engine, the combination 20 with rotary and stationary elements having main buckets and coacting reaction surfaces therein, and also having supplementary buckets and coacting reaction surfaces, of reversing means, and means operated in combination with the reversing means, for admitting motive fluid to the supplementary buckets and coacting reaction surfaces at the time of the operation of the said reversing means.

2. In a turbine engine, the combination 40 with rotary and stationary elements having main buckets and coacting reaction surfaces therein, and also having supplementary buckets and coacting reaction surfaces, of reversing means, means operated in conjunction with the reversing means for admitting motive fluid to the supplementary buckets and coacting reaction surfaces at the time of the operation of the said reversing means, 45 governing means, and means operated thereby for cutting off admission of motive fluid to the said supplementary buckets and coacting reaction surfaces after the engine has reached a predetermined speed of rotation 55 in the new direction of drive.

3. In a turbine engine, the combination 60 with rotary and stationary elements having main buckets and two sets of coacting reaction surfaces therein, the one set for employment when the engine is driven in one direction and the other set for employment when the engine is driven in the opposite direction, the said rotary and stationary elements also having supplementary buckets 65 and coacting reaction surfaces, of a revers-

ing valve for admitting motive fluid to the one or the other of the said sets of main reaction surfaces, another valve, means for operating the first said valve to reverse the position thereof, means operated in conjunction therewith for operating the second said valve to admit motive fluid to the said supplementary buckets and reaction surfaces, governing means, and means operated thereby for again closing the latter said valve after the engine has reached a predetermined speed of rotation in the new direction of drive.

4. In a turbine engine, the combination 80 with rotary and stationary elements having main buckets and two sets of coacting reaction surfaces therein, inclined in opposite directions, the said rotary element having also supplementary buckets, of a reversing valve for admitting motive fluid to the one 85 or the other of the two sets of main reaction surfaces, a supplementary reversing valve having two sets of reaction surfaces therein either of which is adapted for coaction with the said supplementary buckets, and means for reversing the position of the main 90 and supplementary reversing valves.

5. In a turbine engine, the combination 95 with rotary and stationary elements having main buckets and two sets of coacting reaction surfaces therein, the one set for employment when the engine is driven in one direction and the other set for employment when the engine is driven in the opposite direction, the said rotary element having 100 also supplementary buckets, of a reversing valve for admitting motive fluid to the one or the other of the two sets of main reaction surfaces, a supplementary reversing valve having two sets of reaction surfaces 105 therein either of which is adapted for coaction with the said supplementary buckets, and connected means for simultaneously reversing the position of the said main and supplemental reversing valves.

6. In a turbine engine, the combination 115 with rotary and stationary elements having main buckets and two sets of coacting reaction surfaces therein, the one set for employment when the engine is driven in one direction and the other set for employment when the engine is driven in the opposite direction, the said rotary element having also supplementary buckets, of a reversing 120 valve for admitting motive fluid to the one or the other of the two sets of main reaction surfaces, a supplementary reversing valve having two sets of reaction surfaces therein either of which is adapted for coaction with the said supplementary buckets, a supplementary motive fluid admission valve, means for reversing the position of the main and supplementary reversing valves, and means in combination therewith for opening 125 the said supplementary admission valve 130

at the time of the operation of the said reversing valves.

7. In a turbine engine, the combination with rotary and stationary elements having main buckets and two sets of coacting reaction surfaces therein, the one set for employment when the engine is driven in one direction and the other set for employment when the engine is driven in the opposite direction, the said rotary element having also supplementary buckets, of a reversing valve for admitting motive fluid to the one or the other of the two sets of main reaction surfaces, a supplementary reversing valve having two sets of reaction surfaces therein either of which is adapted for coaction with the said supplementary buckets, a supplementary motive fluid admission valve, means for reversing the position of the main and supplementary reversing valves, means in combination therewith for opening the said supplementary admission valve at the time of the operation of the said reversing valves, governing means, and means operated thereby for closing the said supplemental admission valve after the engine has reached a predetermined speed of rotation in the new direction of drive.

8. In a reversing turbine engine, the combination with a rotary element and a reversing valve, of means for temporarily connecting the reversing valve with the rotary element to effect the operation of the said reversing valve, and means for automatically freeing the reversing valve from said rotating element.

9. In a reversing turbine engine, the combination with a rotary element and a reversing valve, of gearing between the said rotary element and the said reversing valve, and a clutch for connecting the said gearing in operative driving relation.

10. In a reversing turbine engine, the combination with a rotary element and a reversing valve, of manually operated means for connecting the said reversing valve in driving relation with the said rotary element, and means operated in the further movement of the engine for disconnecting the said reversing valve from such driving relation.

11. In a reversing turbine engine, the combination with a rotary element and a reversing valve, of manually operated means for connecting the said reversing valve in driving relation with the said rotary element, and means operated by a part moving with the said valve for disconnecting the said valve from such driving relation.

12. In a reversing turbine engine, the combination with a rotary element and a reversing valve, of gearing between the said rotary element and the said reversing valve, a clutch for connecting the said gearing in operative driving relation, manually oper-

ated means for throwing in the said clutch, and means operated by the valve in its movement for throwing out the said clutch.

13. In a reversing turbine engine, the combination with a rotary element and a reversing valve, of a clutch for normally holding the valve stationary, another clutch for connecting the said valve in driving relation with the said rotary element, manually operated means for disconnecting the said stationary clutch means and for connecting the said driving clutch means, and means operated by the valve in its movement for disconnecting the said driving clutch means and again connecting the said stationary clutch means.

14. In a reversing turbine engine, the combination with a rotary element and a reversing valve, of a clutch for normally holding the valve stationary, another clutch for connecting the said valve in driving relation with the said rotary element, a shipper rod for the said clutch means, manually operated means for effecting the movement of the shipper rod in one direction, and means moving with the said valve for operating upon the said shipper lever to move it in the other direction.

15. In a turbine engine, the combination with a rotary element having buckets therein and a stationary element having an admission channel and reaction surfaces for coaction with the said buckets, of an adjustable block also containing reaction surfaces for coaction with the said buckets, and means for adjusting the said block whereby to adjust the relative position of the reaction surfaces therein with respect to the reaction surfaces in the said stationary element.

16. In a turbine engine, the combination with a rotary element having buckets therein and a stationary element having an admission channel and reaction surfaces for coaction with the said buckets, of an adjustable block containing an admission channel for registration with the admission channel in the stationary element, and also containing reaction surfaces for coaction with the said buckets, and means for adjusting the said block whereby to adjust the position of the admission channel therein with respect to the admission channel in the stationary element and also to adjust the relative position of the reaction surfaces therein with respect to the reaction surfaces in the said stationary element.

17. In a turbine engine, the combination with a rotary element having buckets therein and a stationary element having an admission channel and reaction surfaces for coaction with the said buckets, of an adjustable block also containing reaction surfaces for coaction with the said buckets, automatic governor means, and means for adjusting the said block whereby to adjust the relative

position of the reaction surfaces therein with respect to the reaction surfaces in the said stationary element.

18. In a turbine engine, the combination with a rotary element having buckets therein and a stationary element having an admission channel and reaction surfaces for coaction with the said buckets, of an adjustable block containing an admission channel for registration with the admission channel in the stationary element, and also containing reaction surfaces for coaction with the said buckets, automatic governor means, and means for adjusting the said block whereby to adjust the position of the admission channel therein with respect to the admission channel in the stationary element and also to adjust the relative position of the reaction surfaces therein with respect to the reaction surfaces in the said stationary element.

19. In a turbine engine, the combination with rotary and stationary elements having main buckets and coacting reaction surfaces therein and also having supplementary buckets and coacting reaction surfaces, of an adjustable block also containing reaction surfaces for coaction with the main buckets, a governor, and means operated thereby for adjusting the said block whereby to adjust the relative position of the reaction surfaces therein with respect to the reaction surfaces in the said stationary element, the said governor being arranged to adjust the block during the normal operation of the engine, another governor, and means operated thereby after the speed of the engine has fallen below a predetermined point, for admitting motive fluid to the said supplementary buckets and coacting reaction surfaces.

20. In a turbine engine, the combination with a rotary element having main and supplementary buckets therein, and a stationary element having an admission channel and reaction surfaces for coaction with the said buckets, and other reaction surfaces for coaction with the said supplementary buckets, of an adjustable block containing an admission channel for registration with the said admission channel in the stationary element and also containing reaction surfaces for coaction with the said main buckets, a governor, and means actuated thereby for adjusting the said block whereby to adjust the position of the admission channel therein with respect to the admission channel in the stationary element and also to adjust the relative position of the reaction surfaces therein with respect to the reaction surfaces in the said stationary element, the said governor being arranged to adjust the block during the normal operation of the engine, another governor, and means operated thereby after the speed of

the engine has fallen below a predetermined point, for admitting motive fluid to the said supplementary buckets and coacting reaction surfaces.

21. In a reversing turbine engine, the combination with a rotatable element, a reversing valve, and means for temporarily connecting the reversing valve with the rotatable element to effect the operation of the said reversing valve, of auxiliary actuating means for the engine, and manually operated direction selecting means therefor, whereby the engine may be initially operated in either direction by the said auxiliary actuating means and while the operation of the said reversing valve is being effected.

22. In a reversing turbine engine, the combination with a rotatable element, a reversing valve, and means for temporarily connecting the reversing valve with the rotatable element to effect the operation of the said reversing valve, of auxiliary actuating means for the engine including auxiliary buckets carried by the rotatable element and two nozzles for admitting motive fluid thereto in opposite directions, and manually operated valve means for admitting motive fluid to either of the said nozzles whereby the engine may be initially operated in either direction by the said auxiliary actuating means and while the operation of the said reversing valve is being effected.

23. In a reversing turbine engine, the combination with rotary and stationary elements having buckets and reaction surfaces for coaction therewith in either direction of rotation of the rotating element, and a reversing valve, of means for automatically relieving the engine from load during the operation of reversing the direction of rotation thereof.

24. In a reversing turbine engine, the combination with rotary and stationary elements having buckets and reaction surfaces for coaction therewith in either direction of rotation of the rotary element, and a reversing valve, of a shaft coupling, and means therein for temporarily relieving the shaft from load when the said shaft first begins to rotate in a direction opposite to its former direction of rotation.

25. In a turbine engine, the combination with stationary elements having reaction surfaces therein, of a rotor having rings of buckets in circumferential alinement with some of said reaction surfaces and a ring of supplementary buckets opposite other of the reaction surfaces, means for admitting motive fluid to all of said buckets and their coöperating reaction surfaces, and a centrifugal governor arranged to cut off admission of motive fluid from that part of the rotor in which is the ring of supplementary buckets.

26. In a turbine engine, the combination with stationary elements having reaction surfaces therein, of a rotor having a plurality of rings of main driving buckets 5 therein opposite some of said reaction surfaces, and a ring of supplementary buckets opposite other of the reaction surfaces, means for admitting motive fluid to all of said buckets and their coöperating reaction surfaces, said fluid being arranged to act expansively through the different rings of main driving buckets, and non-expansively through the ring of supplementary buckets, and a centrifugal governor arranged to cut 10 off admission of motive fluid from that part of the rotor in which is the ring of supplementary buckets.
27. In a turbine engine, the combination with stationary elements having reaction surfaces therein, of a rotor having rings of buckets in circumferential alinement with some of said reaction surfaces, and a ring of supplementary buckets opposite other of the reaction surfaces, means for admitting motive fluid to all of said buckets and their co-operating reaction surfaces, a centrifugal governor arranged to control the admission of said fluid, and another centrifugal governor arranged to cut off admission of motive fluid from that part of the rotor in 15 which is the ring of supplementary buckets.
28. In a turbine engine, the combination with a rotor having rings of main driving buckets therein, and a ring of auxiliary starting buckets, stationary elements having reaction recesses opposite the main driving buckets, and a fluid admission nozzle opposite said starting buckets, an automatically actuated valve for controlling the admission of motive fluid to the main driving buckets, and a manually actuated valve for controlling said nozzle. 35
29. In a turbine engine, the combination with a rotor having rings of main driving buckets therein, a ring of supplementary buckets and a ring of auxiliary starting buckets, stationary elements having reaction recesses opposite the main driving buckets, other reaction recesses opposite said supplementary buckets, and a fluid admission 40 nozzle opposite the starting buckets, a valve for controlling the admission of motive fluid to the main driving buckets, means for actuating said valve by the movement of the rotor, an automatically actuated valve for controlling admission of motive fluid to the supplementary buckets, a centrifugal governor for controlling said supplementary bucket admission valve, and a manually actuated valve for controlling said nozzle. 45
